CLAIM

The ornamental design for a tripod mount, as shown and described.

DESCRIPTION

FIG. 1 is a top, front and right perspective view of a tripod mount showing the new design in a typical use configuration;

FIG. 2 is a front view of the tripod mount;

FIG. 3 is a rear view of the tripod mount;

FIG. 4 is a left side view of the tripod mount;

FIG. 5 is right side view of the tripod mount; and,

FIG. 6 is a top view of the tripod mount.

The broken-lines in the drawings depict portions of the tripod mount that form no part of the claimed design.
